UNITED STATES PATENT OFFICE.

WALDO D. PUTNAM, OF NEW YORK, N. Y.

DOOR-CHECK.

1,141,485.

Specification of Letters Patent. Patented June 1, 1915.

Application filed August 4, 1914. Serial No. 854,917.

To all whom it may concern:

Be it known that I, WALDO D. PUTNAM, a citizen of the United States, residing in the city of New York, borough of Brooklyn, 5 in the county of Kings and State of New York, have invented a certain new and useful Improvement in Door-Checks, of which the following is a specification.

The invention relates to means for checking and latching sliding doors, and more particularly to the doors of elevator shafts and the like.

The object of the invention is to provide simple, easily applied, inexpensive means 15 for cushioning the impact of the door at the termination of the closing movement, and also for cushioning the latched door on its rebound from such impact.

The invention consists in certain novel 20 features of construction and arrangement by which the above objects are attained, to be hereinafter described and claimed.

The accompanying drawings form a part 25 of this specification and show an approved form of the invention.

Figure 1 is an elevation of a portion of a shaft-door, seen from the interior of the shaft, equipped with the improved check and latch. The succeeding figures are on a 30 larger scale. Fig. 2 is an elevation corresponding to a portion of Fig. 1, showing the check and latch and the immediately adjacent parts. Fig. 3 is a vertical section, partly in elevation, the line of section being 35 indicated by the line 3—3 in Fig. 2. Fig. 4 is a horizontal section taken on the line 4—4 in Fig. 2, showing a portion of the door in plan view.

Similar letters of reference indicate the 40 same parts in all the figures.

A A are the side walls of an elevator shaft, B is a sliding door supported by hanger straps B¹ from a sliding bar B² running on antifriction balls between the tracks 45 or rails B³ B⁴, all of which may be understood to be of the usual or any approved construction.

On the inner face of the door near its closing edge is a rod C¹ mounted to slide 50 vertically in housings C² C³, while held against rotation, and having a collar C⁴ serving as an abutment for a helical spring C⁵ inclosing the rod between such collar and the adjacent housing C³ and abutting at the 55 lower end against such housing. The spring exerts its force to lift the rod, the

upward movement being limited by the contact of a collar C⁵ with the housing.

At the upper end of the rod is a head or dog C extending horizontally, of wedge or V-shape with the sharp angle presented 60 toward the closing edge of the door, and adapted to engage a swinging latch D loosely mounted on a horizontal shaft or bar D¹ slidably supported in the lugs D² D³ 65 of a bracket D⁴ attached to the wall of the elevator shaft or other fixed portion of the shaft equipment. The bar D¹ is arranged to slide endwise in either direction and is maintained in position with the latch about 70 midway between the lugs D² D³ by helical springs D⁵ D⁶, of equal tension, abutting against such lugs at their outer ends, and at the inner ends against collars D⁷ D⁸ fixed 75 on the bar D¹ one on each side of the latch D. The ends of the bar D¹ project through the lugs sufficiently to permit the required endwise movement without disengagement.

On the upper edge of the door is a vertical arm E located to strike the protruding 80 end of the shaft D¹ in the closing movement of the door.

The operation is as follows:—As the door approaches the closed position shown in the several figures, the angular face c of the dog C contacts with the angular face d of the latch D and swings the latter on the bar D¹ to permit the passage of the dog, and engages the square rear face thereof to retain the door in the closed position. Immediately after such engagement the arm E strikes the protruding end of the bar D¹, moves the latter endwise and compresses the spring D⁵ between the lug D² and collar D⁷, thus cushioning the closing movement and causing the door to come to rest noiselessly and without shock. If in the closing movement the door has acquired sufficient momentum to rebound after such cushioning, the rear face of the dog strikes the corresponding adjacent face of the latch with which it is engaged and moves the latter with the bar D¹ in the opposite direction and compresses the spring D⁶ between the collar D⁸ and lug D³, thus softening the rebound while holding the door in the latched condition. The latch D has a nose D⁹ adapted to strike the under face of the bracket D⁴ and thus hold the latch with its angular face d in position to receive the angular face c of the dog. Disengagement is effected by forcing the rod C¹ downward 95 100 105 110

in opposition to its spring C^4 to a sufficient distance to release the dog C from the latch D and to clear the latter in the opening movement of the door.

5 The improved check and latch will serve advantageously with self-closing sliding doors in which the tracks for the door-hangers are inclined downwardly to close the door by gravity, as will be understood, 10 and the mechanism may be varied in size, proportion, and mode of application as found necessary or desirable in adapting the invention to conditions obtaining in various situations.

15 I claim:—

1. In a device of the character set forth, a bar mounted to slide endwise, a latch carried by said bar and arranged to move therewith, a dog carried by the door and adapted 20 to engage said latch in the closing movement of such door and lock the latter, means carried by such door arranged to move said bar endwise after the engagement of said dog and latch, yielding means actuated by 25 the movement of said bar in one direction to cushion the closing movement of such door, and yielding means actuated by the movement of said bar in the opposite direction to cushion the rebound of such door 30 after the engagement of said dog and latch.

2. In a device of the character set forth, a bar mounted to slide endwise, a latch carried by said bar, a dog carried by the door and adapted to engage said latch in the closing movement of such door, an arm on the latter arranged to strike said bar and move it endwise after the engagement of said latch and dog, and means actuated by such movement of said bar to arrest yieldingly 40 the closing movement of said door.

3. In a device of the character set forth, a bracket, a bar mounted to slide endwise therein, a latch carried by said bar, a dog carried by the door and adapted to engage 45 said latch in the closing movement of said door, an arm on the latter arranged to strike said bar and move it endwise after the en-

gagement of said latch and dog, and springs arranged to resist yieldingly the endwise movement of said bar in either direction. 50

4. In a device of the character set forth, a bracket, a bar mounted to slide endwise therein, a latch carried by said bar and mounted to swing thereon, springs on said bar, one on each side of said latch between the latter and said bracket, a dog carried by the door and arranged to contact with said latch in the closing movement of such door and to swing and engage said latch, and an arm carried by such door arranged to strike said bar and move it endwise in one direction against the force of one of said springs after the engagement of said latch and dog, the other of said springs arranged to resist yieldingly an endwise movement of said bar in the opposite direction. 65

5. In a device of the character set forth, a bracket having lugs thereon, a bar slidably mounted in said lugs, a latch carried by said bar and mounted to swing thereon, a collar on said bar on each side of said latch, a spring between each of said collars and its adjacent lug, said latch having an angular face, a dog carried by the door and having an angular face adapted in the closing movement of such door to contact with the angular face of said latch and swing and engage the latter, and an arm carried by such door arranged to strike said bar and move it endwise in one direction in opposition to one of said springs and thereby cushion the closing movement of such door, the other of said springs arranged to resist an endwise movement of said bar in the opposite direction induced through said dog and latch and thereby cushion a rebounding movement of such door. 75 80 85

In testimony that I claim the invention above set forth I affix my signature, in presence of two witnesses.

WALDO D. PUTNAM.
